UNITED STATES PATENT OFFICE.

FRANK N. STEVENS, OF RUTHERFORD, NEW JERSEY.

DESIGN FOR A MUD-GUARD BRACE FOR BICYCLES.

SPECIFICATION forming part of Design No. 33,082, dated August 14, 1900.

Application filed July 7, 1900. Serial No. 22,879. Term of patent 7 years.

To all whom it may concern:

Be it known that I, FRANK N. STEVENS, a citizen of the United States, residing at Rutherford, county of Bergen, and State of New Jersey, have invented and produced a new and original Design for a Mud-Guard Brace for Bicycles, of which the following is a specification, reference being had to the accompanying drawing, forming part thereof, in which I show an isometrical view thereof detached.

As shown in the drawing, the leading or material feature of my design consists in a mud-guard brace formed of wire curved centrally to form a loop *a* and the free ends pro-

vided with brackets *b*, said brackets comprising a rearward projection *c*, perforated as shown at *d*, and an upwardly-extending projection *e*, perforated as shown at *f*, the whole forming a unique design of mud-guard brace.

What I claim is—

The design for a mud-guard brace for bicycles substantially as shown and described.

In witness whereof I have hereunto set my hand this 25th day of April, 1900.

FRANK N. STEVENS.

Witnesses:

Z. HOFMANN,
J. J. HARRINGTON.
